(57) **CLAIM**

I claim the ornamental design for a molded canoe yoke with integral padding, as shown and described.

DESCRIPTION

The present design relates to a molded canoe yoke having an integral padding fixedly attached thereto. The yoke of the present design is molded from a thermo-resin material and incorporates a plurality of perforations at each extremity thereof so as to allow user to cut said yoke in a length more suitable to the width of the central portion of the canoe to which it is to be installed. The padding may be a molded jell body having a pressure-sensitive back so as to fixedly and permanently attach to said yoke.

FIG. 1 is a perspective view of the molded canoe yoke with integral padding of the present design.

FIG. 2 is a top plan view of the molded canoe yoke with integral padding of the present design.

FIG. 3 is a front elevation view of the molded canoe yoke with integral padding of the present design.

FIG. 4 is a rear elevation view of the molded canoe yoke with integral padding of the present design; and,

FIG. 5 is a bottom plan view of the molded canoe yoke with integral padding of the present design.
